US0D1113609S

(12) **United States Design Patent** (10) **Patent No.:** **US D1,113,609 S**
(45) **Date of Patent:** **** Feb. 17, 2026**

(54) **STEERING WHEEL FOR AUTOMOBILE OR
REPLICA THEREOF**

(71) Applicant: **ASTON MARTIN LAGONDA
LIMITED**, Warwick (GB)

(72) Inventors: **Adam MacKerron**, Warwick (GB);
Leighanne Earley, Warwick (GB)

(73) Assignee: **Aston Martin Lagonda Limited**,
Warwick (GB)

(**) Term: **15 Years**

(21) Appl. No.: **29/928,839**

(22) Filed: **Feb. 16, 2024**

(30) **Foreign Application Priority Data**

Aug. 18, 2023 (EM) 015031621-0003

(51) **LOC (15) Cl.** **12-16**

(57) **CLAIM**

The ornamental design for a steering wheel for automobile
or replica thereof, as shown and described.

DESCRIPTION

FIG. 1 is a left isometric view of a steering wheel for
automobile or replica thereof;

FIG. 2 is a front elevation view of FIG. 1;

FIG. 3 is a left side elevation view of FIG. 1;

FIG. 4 is a top plan view of FIG. 1;

FIG. 5 is a bottom plan view of FIG. 1;

FIG. 6 is a rear elevation view of FIG. 1; and,

FIG. 7 is a right side elevation view of FIG. 1.

1 Claim, 7 Drawing Sheets
